UNITED STATES PATENT OFFICE.

RISAKU ISHIYAMA, OF SEATTLE, WASHINGTON.

ELECTRIC SWITCH.

1,104,194.

Specification of Letters Patent. Patented July 21, 1914.

Application filed October 4, 1913. Serial No. 793,321.

To all whom it may concern:

Be it known that I, RISAKU ISHIYAMA, a subject of the Emperor of Japan, residing at Seattle, in the county of King and State of Washington, have invented certain new and useful Improvements in Electric Switches, of which the following is a specification.

This invention relates to improvements in electric switches, and has for its object the provision of time controlled devices for actuating said switch at any predetermined hour and minute of the day.

The apparatus may be employed in any situation where a time-controlled switch is desirable but it is particularly applicable for automobile use in lighting the side- and tail-lights thereof where the car is left standing in an exposed position, as in a street, and it is inconvenient for the owner to be present 20 to turn on the lights.

In the present drawings is illustrated an embodiment of my invention particularly adapted to automobile service.

With the above objects in view, the invention consists in the novel construction of an electric switch and the combination and adaptation therewith of time-actuating devices, as will be fully explained in the following specification, illustrated in the accompanying drawings, and finally set forth in the appended claims.

In said drawings, Figure 1 is a view in front elevation of an embodiment of my invention. Figs. 2 and 3 are vertical sectional views of the same with the switch elements shown in open and closed positions, respectively. Figs. 4 and 5 are detached detail perspective views of elements of the invention.

Referring to said views, the reference numerals 2 and 3 designate front and back walls, respectively, of a casing, including an upper vertically arranged switch compartment 4 and a lower motor compartment 5. Said compartment 4 is lined on its rear side and bottom dividing the two said compartments with insulating material 6 in which are fixedly positioned terminals 7 and 8, respectively, of an electric circuit A. A plunger 9 of non-conducting material is arranged for vertical reciprocative movements

in said switch compartment. A strip 10 of copper or other good conducting material is secured to the rear face of said plunger having its lower end 10¹ extended forwardly below said plunger in vertical alinement with the terminal 8. Strip 10 thus serves as a bridge to close the gap between said terminals when the plunger is in its lowermost position. Terminal 7 includes a leaf 7¹ resiliently protruding into the path of said plunger while end 10¹ of the bridge-strip 10 is curved to afford yielding electrical connections at the respective points. A vertically arranged stem 11 is rigidly secured at its lower end to said plunger and slidably extends through an aperture in the top of the casing 1 where it is provided at its extremity with a knob 11¹. An extension spring 12 is coiled about said stem within compartment 4 having its ends bearing upon said casing top and the plunger, respectively, tending to press the latter downwardly. A flat-spring 13 is secured at one end in a recess at one side of said compartment 4 and formed at its opposite end with a convex portion 13¹ which is adapted to engage within a depression 14 in said plunger for yieldingly securing the plunger in in-operative condition in the upper portion of compartment 4, as indicated in dotted lines in Fig. 2. A trigger is provided to actuate said plunger comprised of a flat resilient vertical member 15 secured and controlled at its lower end within the compartment 5, and a horizontal member or wing 16. Said members are hingedly connected at 17 and the opposite end of said wing is directed through an aperture 18 in the casing to resiliently extend within the path of said plunger.

Within said motor compartment 5 a clock is fitted having its dial 19 at the front of the casing. The works of said clock are not shown except such parts as are required to actuate the trigger aforesaid. The spindle 20 for the hour hand of the clock is provided with a gear-wheel 21 which communicates its rotary motion through intermediate gear-devices 22 to a gear wheel 23 integral with a hub 24 rotatably mounted upon a mandrel 25, see Fig. 5. Said mandrel is provided at its rear extremity with a squared

end 26 to accommodate a turning key (not shown) and at its front end extends outside of said dial 19 where it is provided with a pointer 27 in connection with a minor dial 5 28 upon said dial face 19. Within said compartment 5 a pin 29 projects at right angles from said mandrel and coacts with a cam-face 30 upon the forward end of said hub 24. Member 15 of said trigger is secured at 10 15¹ to the frame of the clock and extends upwardly through aperture 31 in the upper wall of said compartment. Said member is formed with a hole 32 through which said mandrel extends and resiliently presses outwardly upon the hub 24 urging the cam-face 30 of the latter against said pin 29. Said cam-face comprises a wiping-face for said pin, as best shown in Fig. 5, including a notch 33 having an inclined wall 33¹. When 15 the continued rotation of said hub due to geared connection with the spindle 20 presents the notch 33 to the pin 29 the hub jumps outward under the pressure exerted by the spring-member 15. The latter similarly springs outwardly and such movement causes the tripping of the plunger thereabove, as will be presently explained. The continued rotation of the hub causes the pin to wipe upon the inclined portion 33¹ and, 20 by reaction, thrust the hub and member 15 inwardly to their original position.

The ordinary inoperative position of the device is indicated in dotted lines in Fig. 2 with the spring 13 engaging the depression 35 14 holding the plunger in its uppermost position. When it is desired to pre-arrange that the lights shall be turned on at a given time, the mandrel 25 is adjusted until the pointer 27 indicates the selected hour upon 40 the minor dial 28. The plunger 9 is then pressed downwardly out of engagement with said spring 13 until it rests upon the wing 16 of the trigger, being then as shown in full lines in Fig. 2. At the proper time, the rotation 45 of the spindle 20 by the clockwork similarly rotates the hub 24 bringing the notch 33 into register with the pin 29. As aforesaid, the trigger member 15 is then released and draws forwardly sufficiently at 50 its upper end, as indicated in Fig. 3, to release the plunger which descends through force of its gravity and the spring 12 bridging the two terminals 7 and 8 completing the circuit A and lighting the lamp or lamps 55 thereon. The continued rotation of the hub 24 and the spring-pressed engagement of the pin 29 on the inclined portion 33¹ of said cam-face causes the spring member 15 to recede to its original and normal position 60 with the wing 16 projecting within said compartment 4 in the path of the plunger. Should the plunger be in its lowermost position wherein said electric circuit is closed,

when said wing is reentered within the casing, provision is made for said wing to be 65 deflected upwardly, as indicated in dotted lines in Fig. 3, through its engagement with said depression 14 and a spring 34 is provided at its connection with the member 15 to return the wing to its normal horizontal 70 position as soon as the interference is withdrawn. The plunger is desirably provided with a roller or other anti-friction device 35 at its forward lower edge where it is supported by said wing 16 whereby the force 75 required to withdraw said wing when suitably actuated is reduced to a minimum. The lights are extinguished by raising the plunger to its elevated inoperative position, or they may be turned off by a snap or other 80 suitable switch (not shown) in a three-way system of wiring. In the present example, the circuit A is shown including a battery B and a lamp C while D indicates a supplementary circuit having a switch E whereby 85 the lamp may be lighted independently of the time-controlled devices shown. Also it will be understood that while I have described my invention as a unit it may be duplicated or units included to correspond 90 to the requirements of the user. It is found usually desirable to provide separate switch devices for the side-lights and for the tail-lights of an automobile, hence in the illustrated embodiment the apparatus is shown 95 in Fig. 1 as including duplex switch devices designated by the same or corresponding reference numerals and operated by the same clock-mechanism. Thus the member 15 is shown branched at its upper end and supports two elements 16 and associated parts and the casing contains two compartments 4 each containing separate circuit terminals and operative mechanism, as will be readily understood.

Having described my invention, what I claim, is—

1. The combination with a suitable time-controlled mechanical motor, a notched cam driven thereby, a pin coacting with said notched cam limiting the movements of said cam longitudinally of its shaft, a spring-trigger urging said cam into engagement with said pin, and a wing hingedly connected to the free end of said trigger effected in reciprocal movements by the said longitudinal movements of the cam, of a switch closing element adapted to be supported in its open position by said wing in one of the extreme positions of the wing and tripped to close when said wing is withdrawn.

2. The combination with a suitable time-controlled mechanical motor, a notched cam driven thereby, a pin coacting with said notched cam limiting the movements of said cam longitudinally of its shaft, a spring

trigger urging said cam into engagement with said pin, and a wing yieldingly connected at right angles to the free end of said trigger and effected in reciprocative movements by the said longitudinal movements of the cam, of a switch closing element adapted to be supported in its open position by said wing in one of the extreme positions of the

wing and tripped to close when said wing is withdrawn.

Signed at Seattle, Wash., this 27th day of September, 1913.

RISAKU ISHIYAMA.
